Attorney.

UNITED STATES PATENT OFFICE.

CHARLES E. STELLER, OF MILWAUKEE, WISCONSIN.

SASH-FASTENER.

SPECIFICATION forming part of Letters Patent No. 249,209, dated November 8, 1881.

Application filed October 25, 1880. (Model.)

To all whom it may concern:

Be it known that I, CHARLES E. STELLER, a citizen of the United States, residing at Milwaukee, in the county of Milwaukee and State of Wisconsin, have invented certain new and useful Improvements in Sash-Holders; and I do hereby declare the following to be a full, clear, and exact description of the invention, such as will enable others skilled in the art to which it appertains to make and use the same, reference being had to the accompanying drawing, and to letters or figures of reference marked thereon, which form a part of this specification.

15 My invention relates to improvements in that class of sash-fasteners the locking and supporting arm of which is counterpoised by the lifting-arm; and it consists more especially in the stop or lug which is formed in one and the same piece with the lift, serving the threefold functions of a lift conforming to the shape of the hand of the operator, a counterpoise for retaining the supporting-arm against the casing, and a stop to arrest the upward movement, when raising the sash thereby, at the proper point to serve as a lift.

20 My invention is further explained by reference to the accompanying drawing, which represents a perspective view of the same.

25 A represents the window-sash. B is the window-casing. C are supporting-brackets. D is a bracket for locking the window down when in a closed position.

30 E is the window-fastener proper, consisting in two levers arranged at right angles to each other, the general outline of which is similar to the bell-crank lever. It is loosely pivoted at or near its center by bolt or screw F to the sash A.

35 The lower arm, G, of the fastener is so counterpoised by the arm H that it is retained against the casing B.

The lower end of arm G is provided with hook I, which is adapted to engage beneath the catch or bracket D, whereby the window is locked when closed.

40 The lower surface or extreme end of arm G is convex in shape, and is adapted to rest upon the upper surface of brackets C C when supporting the sash when raised.

The upper surface of brackets C C is formed at an angle to the casing, which permits the fastener to be easily adjusted upon them and removed therefrom.

45 The lower surfaces of the brackets C C are slightly convex in shape, so formed to permit the hook I to slide easily over them as the window is raised without the attention of the operator, and the supporting-arm G is so counterpoised by the upper arm that it is thrown back into the locking or supporting position against the casing instantaneously upon escaping contact with the supporting-brackets, and will, upon the sash being lowered, engage upon the first bracket below it, or beneath the 55 catch D if closed, without the attention of the operator.

50 The upper arm, H, of the fastener is provided with a lug or flange, J, which extends backward from the front surface of the sash A in such a manner that when raised it is brought in contact with the edge of the sash and checks the upward movement of the upper arm when at right angles to the sash, in which position said upper arm serves as a lift 55 for raising the sash. The hook I is thrown out of contact with the casing so far that it escapes contact with the brackets C and D, and the arm H is brought to rest in the most convenient position to serve as a lift.

55 The upper surface of the lifting-arm H is nicely shaped to conform to the shape of the thumb and forefinger of the operator, which is applied in the position indicated by the dotted lines representing a person's hand.

60 The fastener represented by dotted lines shows the position for supporting the window when open, while the lower figure thereof represents the position of the parts when the window is closed and locked.

65 The lifting-arm H extends back from the front surface of the sash out of contact with screens or window-blinds, while the front surface of the two arms is formed in the same plane.

70 I do not claim the bell-crank lever E, consisting in the combination of arms G and H, or the catch and lift with which said arms are respectively provided, as I am aware they are not new.

100

What I claim as new, and desire to secure by Letters Patent, is—

In sash-fasteners, the combination, with the lifting-arm H, of lug J, as formed upon the rear edge of the arm and adapted to extend back from the face of the stile or sash A toward the glass and engage against the edge of the stile as it is raised, whereby the upward movement of the arm H is arrested at right

angles to the stile in the proper position to serve as a lift, substantially as and for the purpose specified.

In testimony whereof I affix my signature in presence of two witnesses.

CHARLES E. STELLER.
